UNITED STATES PATENT OFFICE

2,618,948

WELT TURNING APPARATUS

Leonard Brown, Nottingham, and John Edward Lynam, Mapperley, Nottingham, England, assignors to William Cotton Limited, Loughborough, England

Application May 17, 1950, Serial No. 162,449
In Great Britain May 18, 1949

8 Claims. (Cl. 66—96)

1

This invention concerns welt turning apparatus, of Cotton's patent or other straight bar knitting machines, of the type comprising a series of hooked welting instruments which receive thread loops or kinks of an initial welt course, are moved away from the needles at the plain side thereof during the production of at least a portion of the welt fabric and are subsequently advanced to the needles to permit the initial course to be applied to the latter in the act of turning the welt, a bight of the welt fabric being tensioned beneath the instruments at an intermediate stage in the production of the welt by means of a welt stick (or its equivalent) and suitable attached tensioning means so that the loops or kinks held by the instruments are tensioned away from the needles against stops or catches provided on or in association with the instruments. In certain forms of automatic welt turning apparatus on a Cotton's patent or other straight bar knitting machine, it is usual to leave the welting instruments or "welt hooks" engaged with the fabric after the initial course has been restored to the needles, until at a convenient time the operative disengages them by hand. In the design and construction of automatic welt-turning apparatus, this disengagement is one of the features presenting the greatest difficulty.

An object of the invention is to provide improved means for disengaging welting instruments from the fabric after the welt has been turned. The invention is applicable to the machine and apparatus forming the subject of patent application, Serial No. 162,447, filed May 17, 1950.

With the above object in view the invention provides in a Cotton's patent or other straight bar knitting machine employing a welt bar equipped with hooked welting instruments, of mechanism for producing the disengagement of said instruments from the fabric after the welt has been turned, which mechanism comprises means for raising the welt bar and for supporting it pendulously, with the instruments hanging downward and engaged in the fabric, in such manner that as the fabric is drawn away from the needles the instruments swing away from the needles in the unhooking direction. The swinging movement of the instrument may result in a complete unhooking of the instruments from the fabric but if desired the instruments may be subjected to an additional unhooking movement. Therefore, according to a subsidiary feature of the invention, there is provided means for completing the unhooking by lowering the welt bar

and permitting it to swing further in the unhooking direction. The welt bar may come to rest with the welting instruments pointing away from the needle line and whereas the bar may be reversed to its initial attitude by hand if desired, a further feature of the invention resides in effecting the reversal automatically.

The above and other features of the invention are set forth in the appended claims and are disclosed in the detailed description, given by way of example, of the particular embodiment illustrated in the accompanying drawings in which:

Figure 1 is a general sectional view of welt bar control mechanism according to the invention and showing sufficient of the adjacent parts of a knitting machine to permit the latter to be identified;

Figures 2 to 6 are detail views on a larger scale of certain of said parts at different stages;

Figures 7 and 8 are similar views to Figures 2 to 6 but showing the welt bar being restored to its initial attitude;

Figure 9 is a plan view of Figure 1.

In the accompanying drawings the invention is shown as being incorporated in a straight bar knitting machine according to copending patent application, No. 162,447, filed May 17, 1950. Only sufficient of the knitting machine is shown to permit it to be identified but attention is directed to the table 20, frame member 21, main cam shaft 22, needles 1 and sinkers 2, these elements being of conventional kind. In conventional manner the machine may comprise a plurality of divisions each arranged to knit a selvedged blank (although the invention is of course applicable to a simple unit machine, having a single division of needles for knitting a single blank) and in Figure 9 there is shown the majority of the welt bar control mechanism for a representative division; certain elements of mechanism (e. g. shafts) will extend along a plurality of divisions as will be obvious to one skilled in the art.

Considering now the mechanism of a representative division, and referring especially to Figure 1, a welt bar 3 is provided having welting instruments 5 and end pegs 4; the instruments 5 may be as described in the aforesaid patent application. There is also provided at each end of the division of needles a forked arm 6 having a cleft 7 for receiving the pegs 4 at each end of the division of needles. These forked arms 6 may be employed for advancing and retracting the welt bar in the production and turning of the welt (for which reference is to be made to patent application, No. 162,447, filed May 17, 1950), but

according to the present invention they are also utilised to assist in releasing the welt hooks 5 from engagement with the fabric and this operation is carried out conveniently whilst said arms 6 are stationary in the position indicated in the drawings. For further assisting in the welt hook releasing operation, there are provided lifting levers 8 at each end of the division of needles; these levers 8 may have stops 9, 9' for the purpose of controlling the aforesaid retraction and advancement of the welt bar 3 if desired, and for the purpose of the present invention each lever 8 has a forward ledge or part 27 for engaging the pegs 4 of the welt bar 3. Any suitable mechanism may be provided for raising and lowering said lifting levers 8 at desired times; conveniently as shown the levers 8 are fixed on a rotating shaft 23 which is rocked through the medium of arm 24, rod 10 and tappet 11 which is operated by bits on a pattern disc 12 fixed on a pattern control shaft 13.

Welt straps 14 are also provided having at least one hook 15 for hooking onto the ends of a welt stick 26. The straps 14 are attached to the usual draw off roller 16 biased in the winding-up or draw-off direction by weighted cords or the like 19.

In operation it will be assumed that the welt has been produced (conveniently as described in the specification of said Patent application No. 162,447, filed May 17, 1950) and that the welt bar 3 has been retracted to a certain extent by the forked levers 6 (if such levers are employed for the purpose as before mentioned) and by the being-produced fabric F with which the welt-ing instruments 5 are still engaged. At this stage the fabric is being drawn-off by the welt straps and (again if the forked levers are employed as aforesaid) suitable means such for example as a catch 28 cooperating with a notch 29 in a collar or the like, (on a rocking shaft 30, through the medium of which the forked levers 6 may be operated as aforesaid) may be provided for holding the forked levers in the position shown in Figures 1 and 2 i. e. whereat the pegs 4 are above the ledges or parts 27 of the lifting levers 8. The lifting levers 8 now rise and engage the pegs 4 of the welt bar 3 to raise them upwardly along the clefts 7 in the forked levers 6 (Figure 3), and the result is that because the hooks 5 are still engaged in the fabric F the welt bar becomes tilted as shown into an attitude whereat the welt hooks extend substantially vertically downwards from the welt bar. As shown in Figure 4, continued production of the fabric results in a swinging movement of the welt bar 5 about the axis of the trunnion-like legs 4 (which rest on the ledges 27 and are positioned in clefts 7) until the welt-ing instruments 1 incline downwards towards the front of the machine. While in certain constructions this swinging movement may of itself be adequate to unhook the instruments from the fabric, it will usually be found that the hooks of the instruments require to be at such a length that additional unhooking movement must be imparted. For this reason, at an appropriate stage in the rearward swing of the welt bar 3, the lifting levers 8 are lowered to their inoperative position (Figure 5) with the result that the welt bar 3 is lowered until a shoulder part 17 thereof engages guide rails 18; this shoulder 17 thereupon acts as a pivot about which the welt bar rolls or rocks in the unhooking direction so as to raise the hooks of the welt-ing instruments 5 through comparatively small arc such that the hooks be-

come disengaged from the fabric. Finally the welt bar 3 comes to rest upside-down on said guide rails 18 with the welt-ing instruments 5 extending substantially horizontally, away from the needles 1, towards the front of the machine as shown in Figure 6 and with the pegs 4 still engaged in the clefts 7 of the forked levers 6.

While it is within the scope of the invention to invert welt bar 3 by hand so as to place it in condition for the next welt turning operation, this inversion is preferably effected mechanically. For this purpose the lifting levers 8 are again raised at an appropriate time, and desirably this raising takes place when sufficient of the fabric has been produced for the joint of the welt to be located forwardly of the welt-ing instruments as shown in Figure 7. The levers 8, when raised, engage the pegs 4 and raise them in the clefts 7 of the forked levers 6. As a result the welt bar 3 is again suspended with the instruments 5 pointing downwardly as shown in Figure 7; the balance of the welt bar 3 and instruments 5 however is such that the instruments 5 automatically incline towards the needle line as shown. Consequently, upon the lifting levers 8 being next lowered the welt bar 3 automatically lowers until the shoulder or front edge 37 (Figure 7) of the welt bar 3 engages the guides 24 whereupon the welt bar comes to rest with the instruments 5 pointing towards the needles 11 in the desired manner (Figure 8).

If the forked levers 6 are employed as before stated for moving the welt bar to and from the needle line, catch mechanism such as that described above may be employed for preventing (at appropriate time) further rocking of the rocking shaft 30 to take off the tension applied to the fabric by the fork levers 6 and welt-ing instruments 5. The rock shaft 30 may therefore have to be stopped at two different positions in its rotation, and for this purpose there may be provided a pair of the notches 29 at circumferentially spaced locations, and means such for example as a hand lever 31 may be provided for turning the shaft from one position to the other.

We claim:

1. In a straight bar knitting machine having needles and a welt bar equipped with hooked welt-ing instruments for use in turning a welt, mechanism for producing the disengagement of the instruments from the fabric after the welt has been turned, which mechanism comprises the combination of trunnion-like pins on the ends of the welt bar, supports on which the welt bar normally rests, upwardly-extending guide slots along which the pins are movable, lifting devices for engaging beneath the pins to raise and lower the welt bar, means for raising the lifting devices and for thereby lifting the pins in their slots to a position in which the bar hangs pendulously with the instruments pointing downwards and engaged with the fabric and free to swing in the unhooking direction and lowering the lifting devices to lower the pins in their slots and to bring the bar onto the supports and for thereby carrying the latter to fulcrum on the supports in the unhooking direction until upside down.

2. In a Cotton's patent or other straight bar knitting machine employing a welt bar equipped with hooked instruments, a plurality of needles, means for automatically advancing and retracting the welt bar to and from said needles, lifting mechanism for lifting the welt bar to an elevated attitude with the instruments hanging downwards and engaged in the fabric, means for oper-

ating the lifting mechanism to support the welt bar in said manner during retraction of the welt bar and means whereby the welt bar is then supported by the lifting mechanism in a freely pivotal or pendulous manner so that the instruments are swung by the fabric, during its production, in a direction away from the needles to effect partial unhooking of the instruments from the fabric.

3. In a Cotton's patent or other straight bar knitting machine employing a welt bar equipped with hooked instruments, a plurality of needles, means for automatically advancing and retracting the welt bar to and from said needles, lifting mechanism for lifting the welt bar to an elevated attitude with the instruments hanging downwards and engaged in the fabric, means for operating the lifting mechanism to support the welt bar in said manner during retraction of the welt bar, means whereby the welt bar is then supported by the lifting mechanism in a freely pivotal or pendulous manner so that the instruments are swung by the fabric, during its production, in a direction away from the needles to effect partial unhooking of the instruments from the fabric, and means for then lowering the welt bar thus permitting the instruments to swing further from the needles and partially turn over into a reversed attitude to effect further partial unhooking of the instruments from the fabric.

4. In a Cotton's patent or other straight bar knitting machine employing a welt bar equipped with hooked instruments, a plurality of needles, means for automatically advancing and retracting the welt bar to and from said needles, lifting mechanism for lifting the welt bar to an elevated attitude with the instruments hanging downwards and engaged in the fabric, means for operating the lifting mechanism to support the welt bar in said manner during retraction of the welt bar, means whereby the welt bar is then supported by the lifting mechanism in a freely pivotal or pendulous manner so that the instruments are swung by the fabric, during its production, in a direction away from the needles to effect partial unhooking of the instruments from the fabric, and means for then lowering the welt bar, thus permitting the instruments to swing further from the needles into a reversed attitude to effect further partial unhooking of the instruments from the fabric, and supports onto which the welt bar is then lowered and on which it fulcrums to complete the reversing of the welt bar and unhooking of the instruments from the fabric.

5. In a Cotton's patent or other straight bar knitting machine employing a welt bar equipped with hooked instruments, a plurality of needles, means for automatically advancing and retracting the welt bar to and from said needles, lifting mechanism for lifting the welt bar to an elevated attitude with the instruments hanging downwardly and engaged in the fabric, means for operating the lifting mechanism to support the welt bar in said manner during retraction of the welt bar, means whereby the welt bar is then supported by the lifting mechanism in a freely pivotal or pendulous manner so that the instruments are swung by the fabric, during its production, in a direction away from the needles to effect partial unhooking of the instruments from the fabric, means for lowering the welt bar thus permitting the instruments to swing further from the needles and partially turn over into a reversed attitude to effect further partial unhook-

ing of the instruments from the fabric, supports onto which the welt bar is lowered and on which it fulcrums to complete the reversing of the welt bar and unhooking of the instruments from the fabric, and means for inverting the welt bar back to its correct attitude.

6. In a Cotton's patent or other straight bar knitting machine employing a welt bar equipped with hooked instruments, a plurality of needles, means for automatically advancing and retracting the welt bar to and from said needles, lifting mechanism comprising lifting devices engaging pivot pins on the ends of the welt bar for lifting the welt bar to an elevated attitude with the instruments hanging downwards and engaged in the fabric, means for operating said lifting devices to support the pivot pins (and consequently to support the welt bar in said manner) during retraction of the welt bar, and means whereby the welt bar is then supported by the lifting mechanism in a freely pivotal or pendulous manner so that the instruments are swung by the fabric, during its production, in a direction away from the needles to effect partial unhooking of the instruments from the fabric.

7. In a Cotton's patent or other straight bar knitting machine employing a welt bar equipped with hooked instruments, a plurality of needles, means for automatically advancing and retracting the welt bar to and from said needles, lifting mechanism comprising lifting devices engaging pivot pins on the ends of the welt bar for lifting the welt bar to an elevated attitude with the instruments hanging downwards and engaged in the fabric, means for operating said lifting devices to support the pivot pins (and consequently to support the welt bar) in said manner during retraction of the welt bar, and upwardly extending guide slots for receiving the pins in a manner movable along the slots so that the slots and pins, together with the lifting supports, constitute means whereby the welt bar is supported in a freely pivotal or pendulous manner so that the instruments are swung by the fabric, during its production, in a direction away from the needles to afford partial unhooking of the instruments from the fabric.

8. In a Cotton's patent or other straight bar knitting machine employing a welt bar equipped with hooked welting instruments, a plurality of needles, mechanism for producing the disengagement of the instruments from the fabric after the welt has been turned, comprising pivoted upstanding arms having upwardly extending slots, and pivot pins on the ends of the welt bar for engaging in said slots; cam operated truck arm and chain means for operating said arms to advance and retract the welt bar through the medium of said pins; substantially horizontal lifting arms for engaging said pins to lift the welt bar to an elevated attitude with the instruments hanging downwards and engaged in the fabric; cam and truck arm means for raising the lifting arms to support the welt bar in said manner during retraction of the welt bar by the upstanding arms, so that the welt bar is then supported on said lifting arms and in said slots in a freely pivotal or pendulous manner and may be swung by the fabric, during its production, in a direction away from said needles to effect partial unhooking of the instruments from the fabric, and for lowering the welt bar and permitting the instruments to swing further from the needles to turn over into a reversed attitude to effect further partial unhooking of the instruments from the fabric; sta-

tionary bar members onto which the welt bar is lowered and on which it fulcrums to complete the reversing of the welt bar and unhooking of the instruments from the fabric; and the pivot pins being at such locations on the welt bar that when the bar is supported pivotally or pendulously without the instruments engaging the fabric, the instruments incline towards the needles and said cam and truck arm means being arranged to raise the lifting arms (and consequently the pins and welt bar) at an appropriate stage after release of the instruments from the fabric, and then to lower them so that the welt bar fulcrums on the stationary members and is inverted thereby to the correct attitude.
